United States Patent Office

Des. 214,442
Patented June 17, 1969

214,442

RIFLE BUTT HOLDER

Charles M. Marg, 135 Henley Road,
Overbrook Hills, Pa. 19151

Filed Feb. 12, 1968, Ser. No. 10,552

Term of patent 14 years

Int. Cl. D22—02

U.S. Cl. D22—13

FIG. 6.

FIG. 7.

FIG. 1 is a perspective view of a rifle butt holder showing my new design, the fragmental showing of a belt being depicted for illustrative purposes only.

FIG. 2 is a top plan view thereof.

FIG. 3 is a left side elevational view thereof.

FIG. 4 is a front elevational view thereof.

FIG. 5 is a rear elevational view thereof.

FIG. 6 is a bottom plan view thereof.

FIG. 7 is a right side elevational view thereof.

I claim:

The ornamental design for a rifle butt holder, as shown and described.
